UNITED STATES PATENT OFFICE.

HARRY F. WOERNLEY, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

ELECTRIC TRAIN-LINE COUPLING.

1,244,936.

Specification of Letters Patent. Patented Oct. 30, 1917.

Application filed October 8, 1915. Serial No. 54,914.

To all whom it may concern:

Be it known that I, HARRY F. WOERNLEY, a citizen of the United States, residing at Pittsburgh, in the county of Allegheny and 5 State of Pennsylvania, have invented a certain new and useful Improvement in Electric Train-Line Couplings, of which improvement the following is a specification.

This invention relates to coupling devices 10 for connecting the electric train line circuits between the cars of a train, and more particularly to that type of electric couplings in which each of the counterpart couplers of the adjacent cars is provided 15 with a plurality of fixed contacts connected to the respective train line circuits, a movable contact carrier having corresponding contacts, one of said carriers being adapted to be projected to make electrical connec- 20 tions between the respective fixed contacts of the counterpart couplers, and a manually actuated mechanical connection for project- 25 ing one of said contact carriers, such as shown in the prior application of Thomas R. Brown, Serial No. 831,000, filed April 10, 1914.

One of the objects of my present invention is to provide an improved form of mechanical connection operated manually for project- 30 ing the contact carrier, and another object is to provide an improved interlock connection between the mechanism for operating the carrier and the car coupler whereby the car coupler can not be released until 35 the electric contact carrier has been withdrawn. These and other objects will now more fully appear from the following description, and the novel features of my improvement will be set forth in the appended 40 claims.

In the accompanying drawings: Figure 1 is a vertical section of one form of my improved electric coupling device, showing the same suspended from the car coupler which 45 is indicated in side elevation, the section being taken substantially on the line $x-x$ of Fig. 2; Fig. 2, a view of the electric coupling showing one-half in horizontal section and the other half in plan, with the cover re- 50 moved; Fig. 3, a horizontal section of a portion of the car coupler on a larger scale, showing the coupler lock; and Fig. 4, a view, one-half in front elevation of the electric coupling, and the other half showing in

transverse section the contact carrier or 55 slide.

As shown in the drawings, the electric coupling comprises a casing, 1, suspended from the car coupler, 27, by any suitable means, and containing one or more rows of 60 fixed electrical contacts, 2, arranged horizontally and connected to their respective train line circuits. A movable contact carrier, 3, shown in the form of a horizontal slide, and having a series of corresponding 65 connected contact bars, 4 and 5, is mounted to reciprocate longitudinally within the casing, and is adapted to be projected out through the open front end and into the counterpart coupler of an adjacent car to 70 connect the corresponding fixed contacts of the counterpart couplings, and thus close the several train line circuits between the cars.

The contact carrier is provided at both 75 sides with cylindrical projections, 6, mounted on the cylindrical sleeves, 7, supported on the guide rods, 8, carrying the coiled springs, 9, within the sleeves. When the carrier is moved outward, the projections, 6, slide 80 upon the sleeves, 7, without compressing the springs, 9, but when moved in the opposite direction, as when engaged by the carrier of the counterpart coupler, the projection, 6, engages a flange on the sleeve, 7, and 85 moves the same inward to compress the spring which bears against the fixed abutment or sleeve, 10, at its inner end.

As a means for projecting the carrier or slide, I have provided a bell crank lever, 11, 90 pivoted at 12, to the casing, and having one long arm connected by a link, 14, with the slide, and a shorter arm having a pin, 15, projecting into a helicoidal slot, 16, formed in cam portion, 17, mounted on the shaft, 95 18, extending through bearings in the casing, and having handles, 19, for manually operating the same.

It will be noted that the slot, 16, formed in the cam member, 17, is provided with an 100 extension, 16^a, at its end, for the purpose of allowing the free movement of the pin, 15, of lever, 11, of the slide in the counterpart coupler which is forced back to its extreme inner position by the other slide 105 that is being projected.

The car coupler, 27, is preferably of the rigid lock type, having a hook shaped pro-

2
jection adapted to engage a correspondingly shaped recess of the counterpart coupler, and be clamped therewith by a locking lever, 26, which may be operated by a hand lever, 25, having a geared connection, 20, with the vertical stem or shaft, 24, carrying the double cam, 23, engaging the roller, 22, on the rod, 21, for actuating the locking lever, the spring, 28, normally acting to extend 10 the locking lever to the position for coupling.

According to another feature of my improvement, I provide an interlocking means between the car coupler mechanism and the contact carrier, whereby, when the couplers are locked together with the contacts connected, it is necessary to withdraw the contact carrier before the coupler lock can be released. This prevents releasing the couplers when one of the slides, or contact carriers, is in its projected position with the electric circuits closed. Such a means may comprise a pivoted latch lever, 30, having a locking pin, 31, extending through the 25 casing and adapted to engage an aperture in the arm, 32, mounted on the lower end of the actuating shaft, 24, of the coupler. The other end of the latch is adapted to engage a rounded projection, 33, mounted on the 30 slide, 3, when in its normal release position, as shown in Fig. 1, thus forcing the latch against the spring, 34, and withdrawing the pin, 31, from the arm, 32, and permitting the free movement of the handle 35 of the coupler lock. When the couplers are coupled together with one of the slides projected, and the other forced back to its inner position, the spring, 34, actuates the latch, 30, and the pin, 31, enters the aperture of the arm, 32. The parts are then interlocked, and the coupler cannot be released by movement of the handle, 25, until the slide has been returned to its normal release position.

45 When it is desired to release the coupling to separate the cars, the handle, 19, is turned to withdraw the slide, 3, that has been projected into the counterpart coupler, and the spring, 9, acts to return the slide in said 50 counterpart coupler from its inner position to its normal position. The latch levers, 30, in both couplers are thereby withdrawn, leaving the couplers free to be manipulated by the hand levers, 25. These hand levers, 55 25, of both couplers are then turned in either direction to operate their cams and release the coupler locking levers, 26, whereupon the couplers may be separated.

Having now described my invention, what 60 I claim as new and desire to secure by Letters Patent is:

1. In an electric train line coupling, the combination of a casing having fixed contacts connected to the respective train line 65 circuits, a movable contact carrier having

corresponding contacts and adapted to be projected to connect the corresponding contacts of two counterpart couplers, a manually operated cam, and a connection therefrom to the contact carrier. 70

2. In an electric train line coupling, the combination of a casing having fixed contacts connected to the respective train line circuits, a movable contact carrier having corresponding contacts and adapted to be projected to connect the corresponding contacts of two counterpart couplers, a manually operated cam, and a lever having one arm connected to the contact carrier, the other arm being operated by said cam. 80

3. In an electric train line coupling, the combination of a casing having fixed contacts connected to the respective train line circuits, a movable contact carrier having corresponding contacts and adapted to be projected to connect the corresponding contacts of two counterpart couplers, a manually operated cam having a helical slot, and a lever engaging said slot and connected to said contact carrier. 90

4. In an electric train line coupling, the combination of a casing having fixed contacts connected to the respective train line circuits, a movable contact carrier having corresponding contacts and adapted to be projected to connect the corresponding contacts of two counterpart couplers, a manually operated shaft, a cam mounted on said shaft, and a lever actuated by said cam and connected to the contact carrier. 100

5. In an electric train line coupling, the combination of fixed contacts connected to the respective train line circuits, a movable slide having corresponding contacts and adapted to be projected to connect the corresponding contacts of the two counterpart couplers, guide rods at the sides of said slide, coiled springs on said rods, and sleeves slidably mounted on the guide rods and operated by said slides. 110

6. In an electric train line coupling, the combination of fixed contacts connected to the respective train line circuits, a movable slide having corresponding contacts and adapted to be projected to connect the corresponding contacts of the two counterpart couplers, guide rods at the sides of said slide, coiled springs on said rods, and sleeves mounted on said guide rods, the slides having projections at the sides slidably connected with said sleeves. 115

7. In a combined car and electric coupling, the combination of fixed contacts connected to the respective train line circuits, a movable contact carrier having corresponding contacts for connecting the same with the contacts of a counterpart coupler, a manually actuated device for projecting the carrier, a coupler lock, and an interlocking mechanism for preventing the re- 120 130

lease of the coupler lock while the contact carrier is projected.

8. In a combined car and electric coupling, the combination of a movable contact carrier adapted to establish connection between the couplers, a coupler lock, a manually operative stem for actuating same, and an interlocking latch lever between said stem and the contact carrier.
10. 9. In a combined car and electric coupling, the combination of fixed contacts connected to the respective train line circuits, a movable contact carrier having corresponding contacts, means for projecting the carrier to establish electrical connection between the corresponding contacts of counterpart couplers, a coupler lock, and a mechanical interlock between the carrier and

the coupler lock for preventing the release of the coupler lock while the contact carrier 20 is in its projected position.

10. In a combined car and electric coupling, the combination of fixed contacts connected to the respective train line circuits, a movable contact carrier having corresponding contacts, means for projecting the carrier to establish electrical connection between the corresponding contacts of counterpart couplers, a coupler lock, and interlocking mechanism operated by the outward 25 movement of the contact carrier for locking the coupler lock.

In testimony thereof I have hereunto set my hand.

HARRY F. WOERNLEY.
